KEY-LOCKED FASTENING OF ATTACHE CASES AND THE LIKE

Filed Feb. 14, 1947

UNITED STATES PATENT OFFICE

2,516,550

KEY-LOCKED FASTENING OF ATTACHE
CASES AND THE LIKECharles William Cheney, Hockley, Birmingham,
EnglandApplication February 14, 1947, Serial No. 728,705
In Great Britain February 12, 1946Section 1, Public Law 690, August 8, 1946
Patent expires February 12, 1966

3 Claims. (Cl. 70—67)

1

This invention relates to key-locked fastenings of attaché cases, boxes, bags and travel goods of the kind comprising a front plate, a back plate, a dished and flanged spring-loaded bolt slideable between the front and back plates and a pivoted key-operated bolt-locking plate, said bolt being adapted to be manually moved by a knob on the face of the front plate in order that a hasp may be engaged with or disengaged from the bolt through an opening in the front plate.

Fastenings of this kind are necessarily manufactured on a mass production basis in order to cope with the large demand, to ensure that they may be sold to case and travel goods manufacturers at keen and competitive prices, and more particularly, to make such goods available to the purchasing public at reasonable cost. In general, these fastenings are mass produced on power and hand presses and assembled by unskilled labour, and it is most desirable from labour, raw material and machine tool aspects that maximum productive efficiency be exercised in order to reduce the number of process steps to a minimum, thus saving raw material, machine time and labour to utmost advantage which will ultimately reflect upon the purchasing public by way of cheaper, but equally efficient fastenings. It may be appreciated, therefore, that apparent small changes in arrangement or construction of such fastenings have an important bearing on the manufacturing aspect, especially where millions of small parts of an annual output need to be blanked, raised, pierced, bent and assembled so that development resulting in improvements in these fastenings may eliminate one or more process operations and an inestimable saving in labour, raw material and machine time be effected.

It is therefore an object of the invention to provide improvements in fastenings of this kind with a view to simplifying the construction and thereby obtain advantages in manufacture and assembly.

In fastenings according to the invention, the spring for the bolt is of a multi-limb arrangement and is held in the bolt by the flanges thereof and by a lug on the bolt, so that the spring can be embodied in the bolt by fingers of the assembler and the bolt can be inverted for assembly in the back plate without the risk of the spring becoming detached, thus expediting the assembly of the fastenings.

According to a further feature of the invention, the lug on the bolt constitutes an abutment for the locking plate for the purpose of resisting retraction of the bolt.

2

According to another feature of the invention, the multi-limb spring terminates in a curved portion adapted to co-operate with a snap nose on the locking plate for effecting a snap action when the locking plate is key-operated into locking and unlocking positions so that the spring performs the dual function of spring-loading both the bolt and the locking plate. According to further constructional features, the pivot for the locking plate and stops for controlling its angular movement are formed integral with the back plate.

In order that the invention may be clearly understood and readily carried into effect, one embodiment of the fastening will now be described with reference to the annexed explanatory drawing wherein:

Fig. 1 is a topside plan view of the fastening with the front plate removed, the locking plate being shown in a position resisting retraction of the bolt.

Fig. 2 is a topside plan view of the back plate, the bolt and spring unit and the locking plate being removed.

Fig. 3 is a transverse section of Fig. 2 taken on the broken line *a—a*.

Fig. 4 and Fig. 5 show respectively a plan and a side view of the locking plate.

Fig. 6 is an underside plan of the bolt and spring unit.

Fig. 7 is a transverse section of Fig. 6 taken on the broken line *b—b*.

Fig. 8 is a topside plan of the front plate.

Figure 9 is a section taken along the line *c—c* of Figure 1.

In the drawing, the numeral 1 denotes a shallow sheet metal front plate provided with a hasp receiving slot 2 and an opening 1a for receiving a slidable bolt-operating knob 3, 3a, as shown in Figure 9; 4 is a sheet metal back plate, adapted to lie in and to be securely attached to the front plate and provided with integral penetrating prongs 4a for attachment of the fastening to a case or the like, a hasp slot 5 and a recess 6 to accommodate a slidable sheet metal bolt 7 which is adapted to be retracted by the operating knob 3 against the action of a multi-limb spring 8, and to be locked in the shot position by means of a revoluble locking plate 9, mounted in the recess 6 of the back plate 4, under control of a key inserted through the key hole 10 in the operating knob 3, 3a.

A pivot-sleeve 12 is pierced or punched from the back plate 4 and constitutes the axis for 55 the revoluble locking plate 9, and two spaced

stop lugs 13, 13a, are raised from this back plate for use in controlling the angular movement of the locking plate 9 in its bolt-locked and retractible positions. The sheet metal locking plate 9 has a hole 14 which fits over the pivot-sleeve 12, two radially extending stop lugs 15, 15a, a pair of key bit-engaging stumps 16 and a snap nose 17 formed integral with this locking plate. The bolt 7 is formed of sheet metal by pressing and has a peripheral flange 18 and a slot 19 through which the bit of a suitable key can engage the key stumps 16 on the locking plate 9 which lies in the recess 6 and is interposed between the bolt 7 and this recess 6. The bolt 7 has a key peg 1c which extends into the knob 3, 3a, as shown in Figure 9.

On the bolt 7, rearwardly of its nose 1a, is an inwardly directed lug 7b which is raised integrally on this bolt from an edge of the opening or slot 19 and this lug 7b serves the dual purpose of locating one limb 8a of the spring 8 and of forming an abutment for the snap nose 17 on the locking plate 9, thereby to block retraction of the bolt 7 when locked. This lug 7b safely locates the spring 8 so that it can be placed in position in the bolt 7 by the fingers of the assembler and the bolt-spring unit 7, 8, inverted and readily applied to the back plate 4 without risk of the spring 8 becoming detached, thus facilitating handling and expediting assembly of the fastening. It will be seen that the multi-limb wire spring 8 embodies a straight forward limb 8b, an inwardly turned right angular limb 8c, an inner limb 8a parallel to the forward limb 8b and an approximately semi-circular end 8d projecting into the path of the snap nose 17 of the locking plate 9. The limbs 8b, 8c, are retained in the bolt 7 by the flanges 18 as also is the U-shaped bend 8e, and the limb 8a is held by the lug 7b so that this spring is held in the bolt 7 in four principal directions.

It will be seen from Fig. 1 that the locking plate 9 is disposed with its snap nose 17 abutting against the lug 7b which is integral with the bolt 7, thereby resisting retraction of the bolt, the stop lug 15 on the locking plate lying against the lug 13 on the back plate 4, thereby controlling angular movement of the locking plate 9 in a clockwise direction. Turning of the locking plate 9 counter-clockwise, as seen in Fig. 1, by means of a key engaging the key stumps 16, moves the snap nose 17 out of alignment with the lug 7b, the nose 17 snapping past the curved part 8d of the spring when the other controlling lug 15a engages the lug 13a. The bolt 7 can now be retracted against the action of the spring 8. Turning the plate 9 clockwise, as seen in Fig. 1, by means of a key, will snap the nose 17 in a return movement past the curved hump 8d in the spring, again positioning the nose 17 in locking position behind the lug 7b.

The slideable bolt operating knob comprises two members 3, 3a with the part 3a formed of a circular plate member, slightly dished, and having the keyhole 10, with the peripheral edge of the

plate turned in and pressed into a circular opening formed in part 3. This plate has integral lugs 3b which extend through the opening 1a of plate 4 (see Figure 9) and the openings 1d of the bolt 7, and are bent over against the back wall thereof, as shown in Figure 9, to lock the assembly 3, 3a, 4 and 7 together.

What I claim is:

1. A key locked fastening device comprising a perforated front plate and a recessed back plate connected together, a pivot extending into said recess from said back plate, a peripherally flanged bolt slideable in the recess of the back plate, a locking plate seated in the recess formed by the flanges of said bolt and pivoted on said pivot, a lug extending into the recess of said bolt from the body thereof adjacent its forward end substantially midway between the sides of the bolt, a multi-limbed spring in the recess of said bolt supported under pressure between the portion of said flange at the forward end thereof and said lug, said bolt having an opening in the body thereof and said locking plate having projections forming key bit engaging studs projecting through said opening and into said perforation on said front plate, a key peg on said bolt adjacent said studs on said locking plate, said locking plate having a nose engageable with said lug to prevent relative movement between said locking plate and bolt, thereby locking said bolt, said locking plate being rotatable on its pivot to swing said nose out of the path of said lug and into engagement with said spring whereby relative movement between said locking plate and said bolt is obtained against the pressure of said spring, said bolt being slideable by means of a bolt operating knob fastened thereto over said perforation in said front plate, said knob enclosing said key peg and key bit engaging studs.

2. A key locked fastening device according to claim 1, in which the bolt has a hasp engaging portion, and said portion, the bolt lug, the pivot for the locking plate and the key peg are arranged substantially along a medial line extending longitudinally of the bolt.

3. A key locked fastening device according to claim 1 in which said pivot extends into the opening in said bolt, said bolt being freely slideable with respect thereto in the lock.

CHARLES WILLIAM CHENEY.
